CLAIM

The ornamental design for a strut spring compressor, as shown and described.

DESCRIPTION

FIG. 1 is a front perspective view of a strut spring compressor showing my new design;

FIG. 2 is a front elevational view thereof;

FIG. 3 is a rear elevational view thereof;

FIG. 4 is a top view thereof;

FIG. 5 is a right side elevational view thereof, with the left side being a mirror image; and,

FIG. 6 is a bottom view thereof.

The broken line portions of FIG. 1 are for illustrative purposes only and form no part of the claimed design.

FIG. 1

FIG. 2

FIG. 4

FIG. 3

FIG. 5

FIG. 6
